PROCESS AND APPARATUS FOR CONVERTING PETROLEUM HYDROCARBONS

Application filed March 11, 1925. Serial No. 14,641.

This invention relates to improvements in a process and apparatus for converting petroleum hydrocarbons, and refers more particularly to a continuous process operated at relatively high pressure wherein hydrocarbon oils are subjected to a cracking temperature and pressure regulated to prevent any substantial vaporization during the cracking reaction.

Among the objects of the invention are, to provide a process in which low boiling point or gasoline like products are obtained by utilizing the contained heat of the converted products to distill off the lighter fractions under reduced pressure in a separate evaporating zone and thereafter reducing the vapors to what is termed an end point gasoline by a properly regulated refluxing and condensing system; to provide a process which includes an automatic temperature control in the top of the refluxing column in order to definitely regulate the temperature of the overhead material passing from the column which is preferably in the form of a bubble tower; to provide a process, the novelty of which primarily lies in the utilizing of a portion of the contained heat of the cracked materials as they are withdrawn from the zone of reaction to redistill the reflux condensate separated out in the refluxing or dephlegmating tower in a separate redistilling or reboiling stage.

The single drawing is a diagrammatic side elevational view of the apparatus with parts broken away and parts in section.

Referring to the drawing, at 1 is shown a furnace in which are positioned the heating coils consisting of an upper preheating coil 2 and a lower coil 3. Heat is applied to the coils by means of burners shown at 4. Five is a reaction chamber; 6 is an evaporator; 7 is a dephlegmator or refluxing tower preferably of the bubble tower type as diagrammatically shown in the broken away portion; 8 is a reflux condensate reboiler; 9 is a charging pump; 10 is a condenser or cooling box; and 11 is a gas separator.

Describing now briefly the operation, the charging stock, which may be of any desired character such as gas oil, kerosene distillate,

fuel oil, refinery slops or other cracking stocks, is introduced from any convenient source through the line 12 controlled by a valve 13, flowing to the suction side of the pump 9 through the pipe 14. The material is discharged from the pump through a line 15 into a closed coil 16 positioned into the top of the tower, or it may be bypassed by the automatic manipulation of the valve 17 through a mechanism diagrammatically shown at 18 in the top of the tower whereby circulation through the coils 16 is only permitted when the temperature of the overhead material passing from the top of the tower is within a desired range. After passing the valve 17 or through the coil 16 as the case may be, the charging stock proceeds through the line 19 to the preheating coil 2 where it is brought just below a cracking temperature after which it passes to the lower coil 3 where it is rapidly heated to the desired condition to effect a proper degree of reaction or cracking or being discharged into the reaction chamber 5 through the transfer line 20. The velocity of the oil passing through the heating coils and the rate of heating is controlled to prevent any substantial degree of cracking in the coil, thus eliminating the objectionable carbon accumulation in the heating tubes. The time that the oil remains in the heating coils after it has arrived at a cracking temperature is of considerable importance, as it is this condition which causes difficulty due to carbon accumulation. At the same time sufficient temperature must be given the oil in the coils to produce the proper degree of reaction in the cracking stage 5 which is entirely out of the heating zone and where loss of heat is prevented by heavy insulation. The reaction chamber 5 has removable end plates for cleaning purposes.

The oil, after conversion in the reaction stage, is discharged through the line 21 to the coil 22 positioned in the reboiler 8. From the coil 22 it passes through a line 23 at a reduced pressure into the evaporator 6. The valve 24 is interposed in the line 21 and a valve 25 in the line 23. The pressure may be released by either of these valves. With the reduction of pressure, there is distilled off

the lighter fractions of the oil which pass from the top of the evaporating tower 6 through the line 26 into the refluxing column 7. In this latter column 7 the oil vapors are subjected to a dephlegmating or refluxing action in a bubble tower type of construction. The vapors percolate through a plurality of pools of decreasing temperature until they are finally discharged from the top of the tower through the line 27 and are subjected to a final condensing action in the coil 28 positioned in the condenser box 10. The liquid distillate passes through the line 29 regulated by a valve 30 to the gas separator 11 where the gases are separated out and returned through a line 31 regulated by a valve 32 to the burners 4. During the initial stages of conversion or during those periods of operation where there is not sufficient gas to furnish an adequate fuel supply of liquid or gases, fuel may be supplied from any convenient extraneous source through the line 33 controlled by valve 34. The distillate from the gas separator may be drawn off as desired through the line 35 by manipulation of the valve 36.

Returning now to the disposal of the reflux condensate which is separated out as liquid material in the refluxing tower, this liquid, which may be condensed in any of the successive pools, gravitates downwardly and is collected in the bottom of the tower where it is drawn off through the line 37 controlled by a valve 38 and directed to the reflux condensate reboiler 8. Here it is maintained at a definite level by means of an automatic liquid level regulating device diagrammatically shown at 39. This control mechanism manipulates the valve 40 in the discharge line 41 of the reboiling unit. The condensate is maintained by this liquid level regulator at a height sufficient to immerse at all times the coil 22 through which the hot oil from the cracking chamber is circulated. The heat from this hot oil is transferred by conduction to the liquid condensate oil body in which the coil 22 is immersed, giving the liquid sufficient temperature to distill off a substantial portion thereof in the form of vapors which pass out through the vapor line 42 and are returned to the refluxing tower where they are combined with the vapors from the evaporator. The unvaporized material passes out through the line 41 to a cooling coil 43 positioned in the condenser box 10 and this liquid is directed through a line 44 controlled by a valve 45 back to the charging line 14 where it is recirculated with the charging stock for re-treatment in the system. If desired, the unvaporized material from the reboiler may be bypassed around the cooling coil and returned directly through the lines 46 regulated by a valve 47 and line 44 to the charging pipe 14.

The hydrocarbon material unvaporized by

the reduction of pressure in the evaporating stage 6 is automatically discharged by means of the liquid level regulator 47 controlling the valve 48, through the line 49, and after cooling in the coil 50 is directed through a line 51 to a storage. This bottom is composed primarily of relatively heavy material such as fuel oil.

In operation, the oil charge is preferably brought to a cracking heat ranging from 600° F. to 1000° F., more or less, in the heating coil,—normal temperatures during operation ranging from 800° F. to 900° F. The decrease in temperature from the inlet to the outlet of the reaction chamber will normally range from 50° to 100° F. Pressures in the heating and reaction stages are preferably maintained in excess of 500 pounds per square inch, normal pressures being from 600 to 800 pounds per square inch. On discharge from the reaction stage, the pressure is reduced to substantially atmospheric, which is maintained throughout the remaining units of the system. In the treatment of gas oil of 30° to 32° Baumé gravity under these operating conditions, a yield of from 50% to 70% of the original charging stock may be obtained,—the final product, collected as liquid distillate in the gas separator, being endpoint gasoline which requires but little refinement in the way of cleaning, purifying, decolorizing and desulphurizing to make it a marketable product.

The system offers a decided improvement in the utilization of the contained heat of the oil, not only on vaporizing and distilling off the lighter products with a reduction in pressure in the evaporating stage, but also the utilizing of the heat in the cracked products discharged from the reaction stage in redistilling the reflux condensate in a separate stage designated as a reflux condensate reboiler. There is also a decided advantage in having this reboiling stage as a separate unit, as its parts are mechanically more available for repair than when positioned in the bottom of the refluxing tower; also, a unit may be constructed which is adapted to withstand pressure and temperature conditions reducing considerably the cost in constructing such a unit within the bottom of the dephlegmating tower. It will be noted that the reboiler is heavily insulated to prevent loss of heat through radiation.

I claim as my invention:

1. An improvement in the art of oil conversion, which comprises the steps of heating and cracking the oil without distillation, releasing the pressure to cause the lighter fractions to distill off by reason of the contained heat of the oil, subjecting the evolved vapors to a refluxing action in a tower and passing the refluxed condensate to a separate stage of distillation wherein it is subjected to a reheating by contained heat of all of the treated oil sufficient to drive off a con-

siderable portion of the lighter fractions, passing this distilled off portion back to the refluxing tower for retreatment.

2. An improvement in the art of oil conversion for producing lighter from heavier hydrocarbons, which comprises the steps of subjecting the oil to cracking conditions of temperature and pressure in a cracking stage without distillation, releasing the pressure on the heated oil whereby the lighter fractions are distilled off, passing the evolved vapors to a refluxing condenser, passing the refluxed liquid to a separate zone of reheating wherein the material is brought to a boiling temperature by heat obtained from the converted materials finally discharged from the cracking stage, passing the vapors distilled from the reheated reflux back to the said reflux condenser for retreatment and without drawing the unvaporized reflux condensate from the reheating stage.

3. An improvement in the art of oil conversion for producing lighter from heavier hydrocarbons, which comprises the steps of subjecting the oil to cracking conditions of temperature and pressure in a cracking stage imposing sufficient pressure therein to retain the oil substantially in liquid phase without distillation, releasing the pressure on the heated oil in an evaporating stage whereby the lighter fractions are distilled off, passing the evolved vapors to a reflux condenser, passing the refluxed liquid to a separate zone of reheating wherein the material is brought to a boiling temperature by heat obtained from the converted materials discharged from the cracking stage prior to their introduction to the evaporating stage, passing the vapors distilled from the reheated reflux back to the said reflux condenser for retreatment and withdrawing the unvaporized reflux condensate from the reheating stage, and returning said unvaporized reflux condensate directly to the cracking stage for retreatment.

4. An improvement in the art of oil conversion for producing lighter from heavier hydrocarbons, which comprises the steps of heating the oil to a conversion temperature at a relatively high pressure without distillation, passing the oil while in a heated state to a vaporizing stage of reduced pressure in which a considerable portion of the liquid hydrocarbons is distilled off, subjecting the overhead product to a refluxing action and thence to a final condensation, passing all the refluxed liquid to a separate stage of reheating wherein the heat for redistillation of the refluxed products is supplied by the excess heat contained in the converted products discharged from the conversion stage and prior to their introduction into the vaporizing stage, withdrawing the unvaporized products from the vaporizing and reflux reheat-

5. In an apparatus for producing lighter from heavier hydrocarbons by pressure conversion, the combination of heating and cracking means, vaporizing and refluxing elements serially connected to said cracking means whereby the converted oil is passed through the vaporizing element and vapors through the refluxing element subsequent to cracking, a reduction valve between the cracking and vaporizing stages whereby vaporization takes place with the reduction of pressure, a vapor line connected to the top of the refluxing element, a condenser in said vapor line, a separate reflux reheat, a liquid oil line communicating between the bottom of the refluxing element and said reheat, a vapor line from the top of the reheat to the refluxing element, and a closed heating coil within said reheat and interposed in the line communicating between the cracking means and the vaporizing element, and liquid withdrawal lines for the vaporizing element and reheat.

6. An apparatus for converting hydrocarbon oil comprising a heating system, a reaction chamber connected with the heating system, an evaporator and reflux tower connected in series to the reaction chamber and adapted to receive converted oil and vapors respectively, a separate reheating still positioned between the reaction chamber and evaporator adapted to receive the stream of oil discharging from the reaction chamber, a connection for transferring reflux condensate from the reflux condenser to the still wherein it is distilled by the contained heat of said stream of oil and a connection for transferring vapors from said still to the reflux tower.
